UNITED STATES PATENT OFFICE.

ROBERT J. GREEN, OF ST. LOUIS, MISSOURI.

DESIGN FOR A SCARFFPIN OR SIMILAR ARTICLE OF JEWELRY.

57,638.

Specification for Design.

Patented Apr. 26, 1921.

Application filed October 30, 1920. Serial No. 420,822. Term of patent 7 years.

To all whom it may concern:

Be it known that I, ROBERT J. GREEN, a citizen of the United States, residing at St. Louis, in the State of Missouri, have invented a new, original, and ornamental Design for Scarfpins and Similar Articles of Jewelry, of which the following is a specification, reference being had to the accompanying drawing, forming part thereof.

The figure is a perspective view of a scarf pin, showing my new design.

I claim:

The ornamental design for a scarfpin or similar article of jewelry as shown.

ROBERT J. GREEN.
